UNITED STATES PATENT OFFICE.

JOSEPH W. HOPKINS, OF NEW YORK, ASSIGNOR TO GEORGE W. GARNAR,
OF FLUSHING, N. Y.

PRINTING-PRESS.

SPECIFICATION forming part of Letters Patent No. 271,333, dated January 30, 1883.

Application filed January 16, 1882. (No model.)

To all whom it may concern:

Be it known that I, JOSEPH W. HOPKINS, of the city and State of New York, have invented an Improvement in Printing-Presses, 5 of which the following is a specification.

Printing-presses have been made with a chase and form suspended below a bed, the types being raised for inking and pressed down upon the paper laid upon the platen, and an 10 apron has been drawn along over the platen to prevent injury by offsets.

My improvement is for simplifying the construction of the press, for regulating the position of the ink-plate to the types, so that the 15 same will be properly in line when the roller passes from one to the other, and for moving the inking-roller and applying the proper pressure to the same for inking the types.

In the drawings, Figure 1 is a vertical section of the press, and Fig. 2 is an elevation at the side where the sheets are fed in. Fig. 3 is a section in larger size of part of the ink-table.

The frames A A are united by tie-bolts b and by the impression-platen c. These frames 25 are adapted to receive the parts hereinafter described.

The main driving-shaft e is in bearings upon the frames A A, and it is provided with a driving-pulley, and by preference with a fly-wheel, 30 e'. The crank-shaft f is connected to the driving-shaft by the wheel f' and pinion f².

At the ends of the crank-shaft f, outside the frames A A, are the cranks g and connecting-rods h to the follower or bed k, which is adapted 35 at its ends to sliding up and down the guides or openings in the frames A A, and there are the projecting studs i, that receive the upper ends of the connecting-rods h, so that the bed is raised and lowered by the action of the 40 cranks g.

The chase and types l are fastened upon the under side of the bed in any convenient manner.

There are tables m m for the sheets to be 45 printed. These are on the same level as the platen c, and the tympan or smut-sheet n is passed across the platen and wound upon the rollers o and p, there being guide-bars o' p' at the level of the platen, around which the sheet 50 passes.

At one end of the roller o is a ratchet-wheel,

and the lever q and hook-pawl 3 are employed to rotate the roller o progressively, said lever being moved at the longer end by a stud, 4, on one of the connecting-rods h, and the spring 5 returning the lever to a normal position and causing the pawl to take up another tooth on the ratchet. By this means the apron is moved along progressively as the printing is effected, the apron being drawn off the roller p as it is 60 wound upon the roller o. It may be wound back upon the roller p by a handle or crank applied to the end of the shaft of the roller p.

The inking-table s is circular. It is provided with a ratchet-wheel, s', screwed to the back, 65 and between the table and ratchet-wheel is the flat disk-head of the stationary axis t for supporting such bed. This axis is made with a screw-thread on its surface. It passes through an eye at the end of the arm u, that 70 extends out from a cross-bar, u', attached to the side frames, A A, and there are nuts upon t above and below the arm u, so that the axis of the ink-table can be moved up or down to adjust the edge of the ink-table in its proper 75 relative position to the surfaces of the types, so that the inking-roller v may pass freely from such types to the ink-table, or the reverse.

The inking-roller v is supported at its ends in bearings at the lower ends of the swinging arms w, the upper ends of such arms being round, as at 6, and passing through enlargements of the rock-shaft v', that is in bearings at the upper ends of the frames A A.

The link 8 from one of the connecting-rods 85 h to an arm, 9, upon the rock-shaft v', serves to give the required amount of movement, and there are guideways at 10 upon the inner faces of the frames A, beneath which the ends of the inking-roller axis pass, and the springs 14 90 serve to draw the arms w endwise and press the inking-roller against the types; but these guides prevent the inking-roller being lifted by the springs as it is passed from the types to the ink-table, or the reverse.

The arm 9 at the end of the rock-shaft has a clamping-screw at its eye, so that the parts can be adjusted to move the inking-roller across the face of the types at the time the bed reaches its highest point, and then move back across 100 the face of the types and pass to the ink-table s, where the ink is worked and spread

by the roller rolling across it. This ink-table is partially turned each movement of the press by the action of the lever 12, pawl 13, and pusher 14, that receives motion from the arm 5 16 on the rock-shaft v' . By moving this arm upon the rock-shaft its end will act upon the pusher at an earlier or later period in the movement of the rock-shaft and cause the pawl to take up one or more teeth on the ratchet-10 wheel and turn the inking-table a greater or less distance each movement of the press.

I claim as my invention—

1. The combination, with the type-bed, guided at its ends by the slides in the frames A, of 15 the connecting-rods, actuating cranks, inking-table, the rock-shaft v' at the top of the frames, the arms w , sliding through the rock-shaft, the

inking-roller v , carried by such arms and passing across below the inking-table and the types, the contractile springs 14, the arm 9 upon the 20 rock-shaft, and the link 8 to the connecting-rod h , substantially as set forth.

2. The inking-table s and ratchet-wheel s' , in combination with the stationary screw-axis, having a flat disk-head, the stationary arm u , 25 and the nuts upon the screw above and below the arm t , for adjusting the inking-table up or down, substantially as set forth.

Signed by me this 7th day of January, A. D. 1882.

JOSEPH W. HOPKINS.
